[57] CLAIM

The ornamental design for a fitting for a valve switch, as shown and described.

DESCRIPTION

FIG. 1 is a perspective view of a fitting for a valve switch showing my new design;

FIG. 2 is a left side elevational view thereof;

FIG. 3 is a top plan view thereof;

FIG. 4 is a right side elevational view thereof;

FIG. 5 is a front elevational view thereof;

FIG. 6 is a rear elevational view thereof; and,

FIG. 7 is a bottom elevational view thereof.
